UNITED STATES PATENT OFFICE.

EDWARD C. WILSON, OF WASHINGTON, DISTRICT OF COLUMBIA.

DESIGN FOR A PUZZLE-BOARD.

43,452.

Specification for Design.

Patented Jan. 14, 1913.

Application filed December 12, 1912. Serial No. 736,411. Term of patent 7 years.

To all whom it may concern:

Be it known that I, EDWARD COMSTOCK WILSON, a citizen of the United States, and a resident of Washington, District of Columbia, have invented a certain new, original, and ornamental Design for a Puzzle-Board, of which the following is a specification, reference being had to the accompanying drawing, forming part thereof.

The figure is a plan view of a puzzle board, showing my new design.

I claim:

The ornamental design for a puzzle board, as shown.

EDWARD C. WILSON.

Witnesses:

E. E. WEAVER,
L. N. GILLIS.
